UNITED STATES PATENT OFFICE.

JAMES K. BRADLEY, OF CLEVELAND HEIGHTS, OHIO, ASSIGNOR TO THE NATIONAL SYSTEM OF BAKERIES CO., OF CLEVELAND, OHIO, A CORPORATION OF OHIO.

BAKING-OVEN.

1,385,662.

Specification of Letters Patent. Patented July 26, 1921.

Application filed October 13, 1919. Serial No. 330,440.

To all whom it may concern:

Be it known that I, JAMES K. BRADLEY, a citizen of the United States, and a resident of Cleveland Heights, county of Cuyahoga, 5 and State of Ohio, have invented a new and useful Improvement in Baking-Ovens, of which the following is a specification, the principle of the invention being herein explained and the best mode in which I have 10 contemplated applying that principle, so as to distinguish it from other inventions.

The present invention relates to baking ovens particularly designed for use in bakeries in which the baking is done in small 15 stores on the street in full view of the public. In such bakeries the usual large heavy oven cannot be used as the floors are not ordinarily constructed to carry heavy loads and the ovens cannot be installed or removed 20 readily because of their size. More particularly then, the present invention relates to an oven suitable for use in this type of bakeries, in which provision is made so that the interior of the oven may be visible at all 25 times, not only to the bakers but to the public as well.

Provision is also made whereby the oven 30 may be assembled in place on the floor quickly and easily without requiring skilled mechanics, and the oven may be taken apart 35 as easily, the parts fitting snugly together and being so made as to require no fitting or cutting in assembly. To the accomplishment of the foregoing and related ends, said invention, then, consists of the means hereinafter fully described and particularly pointed out in the claims.

The annexed drawing and the following 40 description set forth in detail certain mechanism embodying the invention, such disclosed means constituting, however, but one of various mechanical forms in which the principle of the invention may be used.

In said annexed drawing:

45 Figure 1 is a perspective view of my improved oven showing the door open for the insertion or removal of the baking pans; Fig. 2 is a vertical section through the oven; Fig. 3 is a perspective view similar to Fig. 50 1 but showing the door closed; Fig. 4 is an end elevation of the oven; and Fig. 5 is a section of a detail of the joint between panels.

The present baking oven consists of suitable end members 1 having legs 2, these end

members being an open frame work which is provided with central hubs 3 in which are journaled a shaft 4 mounted centrally through the oven. As shown, the end members are eight sided, the lower part being roughly rectangular and the upper part being decagonal in shape. These end members have an inturned flange 5 turned inwardly and extending around the member and this flange is provided with a series of apertures 6.

Fitting closely within the flange and against the frame work is a suitable inclosing plate 7 which is formed of two sheets of metal separated by an insulating lining of asbestos or the like, the two sheets being held together and to the frame work by bolts 8 or the like. In Fig. 4, I have shown the two upper openings in the end member as being suitably closed by glass windows 9 so that the interior of the oven may be seen from the end.

One of the ends is provided with the driving mechanism for the shaft 4, this driving mechanism consisting of a spur gear 10 secured to the extending end of the shaft and in mesh with a small gear 11 carried on a shaft 12 rotatably mounted on the end member. A worm wheel 13 is mounted on the same shaft 12 and is driven by a worm screw 14 on a shaft 15 carried in suitable bearings on a bracket 16 mounted on the end member. The other end 17 of the wormscrew is provided with a pulley wheel 18 adapted to be driven by a belt 19 from any suitable source of power such as an electric motor or the like.

The oven consists of the two end members which are connected by panels or plates 20 which fit within the flanges on the end members. These panels are secured to the end members by means of bolts 21 which pass through the apertures in the flanges and through aligned apertures in the ends of the panels. Each panel is made up of two sheets of metal 22 and 23 between which is placed asbestos 24 or other suitable insulating material and the two sheets are held together by bolts 25 so that the panels may be handled and put in place quickly and easily.

The edges of the panels are made as best shown in detail in Fig. 5, the outer sheet 22 being bent along its edge 26 at the correct angle for the next panel and extending beyond the panel proper. The inner sheet 23

is bent up toward the outer sheet and then along the edge 26 to form the extending lap 27. The next adjacent panel 28 is formed in the same way except that the lower sheet 29 is bent and the outer sheet 30 is bent to conform therewith to make the lap 31 which connects the panel 23 on its inner surface. Bolts 32 are passed through apertures 33 in the panels and extending laps to secure 10 the panels together and prevent the escape of heat from the interior of the oven.

The panels are all formed in the same way but one of the sides 35 is merely a frame work and to inclose this side a door 36 is provided which is pivoted to the side panel 37 by means of hinges 38. A handle 39 is mounted on the door, and cam locks 40 are mounted on the next upper panel to secure the door tight against this panel. This door 20 is provided with a series of windows 41 made of glass or other transparent heat resistive material and are mounted on the door by suitable frame work 42. Two such doors may be provided, one on either side of the oven if desirable.

Within the oven, on the centrally extending shaft, are mounted two octagonal wheels or spiders 43 which are keyed or otherwise secured to the shaft and these wheels are 30 provided with pins 44 at the angles between the sides. The trays 45 for the baking pans 46 are carried on these pins by means of apertured ears 47 on the ends of the trays which receive the pins and allow pivotal movement so that the trays at all times retain their horizontal position.

On one end of these trays I have shown vertical plates 48 which will be formed of metal which is enameled and which contains 40 advertising or descriptive matter so that as the trays revolve they will become visible through the windows. The present oven will, of course, be heated in any suitable manner.

It will be seen that the oven is constructed of a very few number of parts, which can be bolted together quickly and easily and as easily taken apart. This is of great advantage in the present type of bakeries where 50 small stores are used in which the ovens must be assembled. The oven itself consists merely of the end members and the panels and doors. The shaft may be withdrawn and the trays, spiders and pans removed 55 so that the whole oven can easily be brought into a store room through the ordinary door and assembled in place on the floor. The panels are units and contain the necessary insulation and are so formed that when overlapped and bolted together they make tight

joints thus conserving the heat. The oven as a whole is very light in weight and the large windows in the ends and door permit the ready inspection of the interior at all times, thus allowing the public to view the 65 entire baking operation.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a baking oven the combination of end members provided with inturned apertured flanges, and panels adapted to be removably mounted between said end members, said panels having abutting ends and extending portions adapted to overlap, such overlapping portions being removably bolted together, said panels having apertures in their ends adapted to be alined with such apertures in said flanges and bolts adapted to pass through such alined apertures to secure said panels to said end members.

2. In a baking oven the combination of end members provided with inturned apertured flanges, and panels adapted to be removably mounted between said end members, said panels having abutting ends and extending portions adapted to overlap, such overlapping portions being removably bolted together, said panels having apertures in their ends adapted to be alined with such apertures in said flanges and bolts adapted to pass through such alined apertures to secure said panels to said end members, and a door provided with transparent windows mounted in one of said panels.

3. In a portable oven, the combination of end members comprising end frame members provided with inturned apertured flanges, plates mounted in said frame members to close the same, panels adapted to be removably mounted between said end members, said panels having abutting ends and extending portions adapted to overlap, such overlapping portions being removably bolted together, said panels having apertures in their ends adapted to be alined with such apertures in said flanges, both adapted to pass through such apertures in said flanges to secure said panels to such frame members, and a door provided with transparent windows mounted in one of said panels.

Signed by me, this 10th day of October, 1919.

JAMES K. BRADLEY.
